UNITED STATES PATENT OFFICE.

WILHELM WACHTEL, OF BERLIN, GERMANY, ASSIGNOR TO THE FIRM AKTIENGESELLSCHAFT FÜR CHEMISCHE PRODUKTE VORMALS H. SCHEIDEMANDEL, OF BERLIN, GERMANY.

METHOD OF OBTAINING SOLIDIFIED GRANULES OR PEARLS FROM LIQUIDS.

Application filed June 29, 1925, Serial No. 40,363, and in Germany December 15, 1924.

This invention concerns the production of solid globules, granules, drops or so-called "pearls" from liquids consisting of substances in melted condition or solutions 5 thereof which are in sufficiently concentrated condition to solidify on cooling.

Proposals have already been formulated by us whereby solutions of substances such as glue, gelatine or the like are caused to 10 pass into a cooling fluid in such a way that the substances solidify as separate globules therein.

The employment of liquid cooling baths naturally entails the subsequent separation 15 of the globules from the cooling liquid, an operation necessitating special apparatus and being accompanied by a loss, if only small, of cooling liquid.

By means of the improved method of this 20 invention such loss can be avoided and granules of predetermined size and shape can be obtained.

The improved method consists in transforming liquids consisting of melted substances or solutions of substances into granulars or pearls by causing the liquids in the 25 form of drops, to fall on to a cooling surface adapted to travel underneath the point of discharge at a rate corresponding to that 30 of the discharge of the liquid, the granules or pearls being removed from the cooling surface when sufficiently solidified.

The improved method is especially suited for the treatment of warmed solutions of 35 colloidal substances such as glue, gelatine and the like, but it may also be applied to substances of other kinds.

It is known, per se, and especially in the 40 margarine industry, to spread semi-fluid masses over a cooling surface and cause them to solidify by imparting a travelling movement to the surface and adhering mass, the solidified or crystallized mass being then detached by means of scrapers or the like. A 45 definite granular form cannot, however, be imparted to the product by this known method, the product, on the contrary, being discharged as an amorphous mass or in flakes.

50 On the other hand, it is novel to deliver a liquid in the form of separate drops on to a moving cooling surface in such a way that each drop remains separate, and furnishes a granule or "pearl" on solidifica-

tion. With the method of this invention it 55 is therefore possible, by suitably adjusting the dropping device, to obtain accurate sizing of the individual granules.

The apparatus for carrying the method into practice is comparatively simple and 60 can take various forms so long as there is coaction between a dropping device, fed with the liquid (such as a solution of a gelatinizing colloid) and a moving cooling surface 65 underneath, said cooling surface preferably making a complete circuit in order to render 70 the operation continuous. Such cooling surfaces are already known in the art in many forms, such as belt conveyors, notary tables, cooling drums and the like.

A typical embodiment of an apparatus for carrying out the new method is diagrammatically illustrated in the drawing in which:—

A dropping device *a*, comprising a series 75 of dropping nozzles or the like, is arranged vertically above a revolving cooling drum *b* mounted on a horizontal axis. The series of dropping nozzles may extend across the full width of the drum, but the nozzles are set at such distance apart that the falling drops cannot come into mutual contact and coalesce. When the drum—charged with a cooling medium in known manner—is rotated in the direction of the arrow, the 80 dropping device will deposit successive parallel rows of drops on to the outer surface of the drum, which drops will gradually solidify, under the influence of the cooling 85 surface, while being carried round on the latter. A scraper *c*, which detaches the finished granules or pearls, acts on the cooling surface at a suitable distance from the charging point.

The shape of the resulting granules can 90 be modified by adjusting the distance between the dropping device and the surface of the drum.

It may be advantageous to allow the drum 95 and adherent granules to pass through a cooling bath during a longer or shorter period of its course between the charging and discharging points on the drum. Such a cooling bath *d* is shown on the drawing as being located beneath the shaft of the drum *b*, which latter is immersed in a cooling bath for a portion of its periphery. An endless belt of which a portion *e* is shown,

passes through the bath substantially concentric with the drum, to receive the finished granules which are scraped from the surface of the drum *b* by the scraper *c*; this belt *e* will likewise serve to carry any granules which may be discharged from the surface of the drum before encountering the scraper *c*.

The belt *f* is provided for driving the drum *b* continuously.

It will be noted that whether the cooling bath is used or not, the drops pass for more than half the circumference of the drum.

What I claim is:—

- 15 1. The method of obtaining solidified granules from hot solidifiable liquids which consists in forming the liquid into drops, causing the drops to fall upon and adhere to a surface, moving the surface continuously to present new points for the reception of further drops, and continuously maintaining the surface at a low temperature to gradually solidify the drops, passing the drops while adhering to the surface through a cooling bath, and removing the solidified drops from the surface.
- 20 2. In an apparatus for forming solidified granules from liquids, a liquid container, a drop-forming device to receive liquid from said container and deliver it in the form of falling drops, a device presenting a surface

adapted to travel across the path of the drops and to which the drops will adhere, means to continuously cool said surface, and a scraper to separate from the surface the solidified granules formed from said drops.

3. In an apparatus for forming solidified granules from liquids, a liquid container, a drop forming device to receive liquid from said container and deliver it in the form of falling drops, a device presenting a surface adapted to travel across the path of the drops and to which the drops will adhere, means to continuously cool said surface, a cooling bath disposed in the bath of said surface as it travels, and a scraper to separate from the surface the solidified granules formed from said drops.

4. In an apparatus for forming solidified granules from liquids, an internally cooled cylinder having an outer surface at which the drops will adhere, means to rotate said cylinder on a horizontal axis, a drop-forming device to deliver separate drops onto the surface of said cylinder, a cooling bath in which said cylinder is immersed, and a scraper to remove the solidified granules from said cylinder after contact with the bath.

In testimony whereof I have signed my name to this specification.

WILHELM WACHTEL.
